INVENTOR:
Walter J. Baker
BY Adam E. Fisher
ATTORNEY

UNITED STATES PATENT OFFICE

WALTER JAMES BAKER, OF WYCKOFF, NEW JERSEY

LADDER SHOE

Application filed June 4, 1931. Serial No. 541,985.

This invention relates to ladder shoes or adjustable extensions for ladders to enable workmen or others to conveniently set up a ladder upon a sloping ground or other surface.

The main object of the invention is to provide a ladder shoe or extension in a simple, durable and efficient form and which may be mounted on the rail of a ladder and easily 10 and quickly extended therefrom and adjusted to any desired length to allow use of the ladder upon sloping ground, stairways and the like.

Another object is to provide a device of 15 this kind which may be easily and quickly adjusted to fit a ladder rail of practically any size and which may be easily attached to and detached from the latter.

With these and other objects in view as 20 will appear, the invention resides in the novel construction and arrangement of parts as hereinafter set forth and claimed, reference being had to the accompanying drawing wherein:

25 Figure 1 is a front view of the lower portion of a ladder showing the invention applied thereto and disposed in position to support the ladder upon a sloping surface.

Figure 2 is an enlarged side view of the 30 structure shown in Figure 1.

Figure 3 is an enlarged section along the line 3—3 in Figure 2.

The invention comprises a bracket or attaching plate 1 of L-shaped cross section and 35 comprising a relatively narrow front web 2 and wider side web 3, each of which near their ends are provided with extended ears 4 having elongated slots 5. A portion of the lower end of the side web 3 is turned inward 40 at right angles to provide a ladder rest 6 adapted to support the lower end of either of the ladder rails A of a conventional ladder. The front and side webs 2 and 3 of the bracket 1 are adapted to engage the front and 45 outer side faces of the ladder rail A as shown. Clamping bolts 7 of L-shaped form and threaded adjacent each end as shown at 8 are provided and the opposite ends of each bolt 7 are extended outward through the slots 5 50 in the ears 4, one bolt at the top of the bracket

1 and one at the bottom. Wing nuts 9 are threaded on the ends of the bolts 7 and the arrangement is such that by drawing these nuts 9 up tight against the bracket 1, the bolts 7 are pulled tight against the rear and 55 inner faces of the ladder rail A securely fastening the bracket thereto. This construction permits the mounting of the bracket on ladder rails of practically any cross sectional dimension and shape since the wing nuts 9 60 on each end of the bolts 7 may be adjusted separately or together to vary the effective or gripping length of each leg of the bolts. The provision of the elongated slots 5 in the ears 4 allow this manipulation of the bolts. 65 To remove the bracket 1 from the ladder rail it is only necessary to loosen the nuts 9 and slip the bracket endwise from the rail.

Extension leg slideways 10 are provided 70 adjacent the upper and lower ends of the side web 3 of the bracket 1 and each slideway is formed of a pair of spaced side blocks 11 and a cover or cap 12 secured thereto by screws 13. The extension leg 14 is elongated in form and is slidably mounted through the slideways 10 and is provided at its lower end with a foot or shoe 15. A cotter key 16 or similar element in the upper end of the leg 14 prevents the same from sliding downward entirely through the slideways 10. Two pivot 75 lugs 17 are extended from the web 3 of the bracket 1 between the slideways 10 and on each side of the extension leg 14 and a pawl or dog 18 is pivotally mounted between these lugs on a pin 19. The pawl or dog 18 includes a handle or finger piece 20 and is so shaped that its upper portion normally counterbalances its lower portion and causes the latter to rest in engagement with the outer 80 face of the extension leg 14. This outer face of the extension leg has a plurality of ratchet teeth 21 with which the pawl 18 engages so that the leg may be held in any suitable extended position thereby. A set screw 22 is threaded through one of the pivot lugs 17 85 and may be brought to bear upon the extension leg to prevent the same from sliding downward of its own weight through the slideways 10.

In use the bracket 1 is mounted on the lad- 100

der rail A in the manner described and with the extension leg 14 pulled upward and held by the set screw 22. The latter is then placed in the desired position and the set screw 22 loosened, permitting the leg 14 to slide downward of its own weight until its shoe 15 engages the surface as shown in Figure 1. The engagement of the pawl 18 with the teeth 21 holds the leg in this extended position for use. By simply turning the ladder the leg 14 will allow its use upon ground or surface sloping in the opposite direction. Thus it will be seen that the device is particularly convenient in use as well as being compact, simple and durable in construction.

15 While I have herein set forth a certain preferred embodiment of my invention it is understood that I may vary from the same in minor structural details so as best to construct a practical device for the purposes intended, 20 not departing from the spirit of the invention and within the scope of the appended claims.

I claim:

1. In a device of the kind described, a bracket L-shaped in cross section and including front and side webs, ears formed on the webs, the said ears having elongated slots, L-shaped bolts having their ends extended through the slots, nuts threaded on the ends 25 of the bolts, a ladder rest formed on one end of the bracket, an extension leg slidably mounted on the bracket, and means for securing the extension leg in an adjusted position.
2. In a device of the kind described, a bracket L-shaped in cross section and including front and side webs, ears extended from the webs and having elongated slots, L-shaped bolts having their ends extended 30 through the said slots, nuts threaded on the bolts outwardly of the ears, a ladder rest formed on the lower end of the bracket, spaced vertically aligned slideways on the side web, an extension leg slidably mounted through the slideways, ratchet teeth on the outer face of the extension leg, pivot lugs 35 extended from the side web of the bracket at each side of the extension leg, a pawl pivoted between the pivot lugs for engagement with the ratchet teeth on the extension leg and a set screw threaded through one of the pivot lugs for engagement with the extension leg.

In testimony whereof I affix my signature.
WALTER J. BAKER.
